CLAIM

The ornamental design for a telephone, as shown and described.

DESCRIPTION

FIG. 1 is a front and right side perspective view of a telephone showing my new design;

FIG. 2 is a front elevational view thereof;

FIG. 3 is a rear elevational view thereof; and

FIG. 4 is a right side elevational view.

The abbreviated showing of the cord is for ease and facility of illustration.

FIG.1

FIG.2

FIG. 3

FIG. 4
